CLAIM

The ornamental design for a CD player, as shown and described.

DESCRIPTION

FIG. 1 is a perspective view of a CD player showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, left, bottom side perspective view thereof. The broken lines in the drawings depict portions of the CD player that form no part of the claimed design.

Any shading and cross-hatching are not features of the design but are utilized to illustrate the surface contours of the CD player design in the drawings.
